HOLDER FOR TAPE CASSETTES OR SIMILAR ARTICLE

Maxwell H. Connan, 53 Roosevelt Ave.,
Glen Head, N.Y. 11545

Filed Apr. 22, 1970, Ser. No. 22,565

Term of patent 14 years

Int. Cl. D6—01, 99

U.S. Cl. D33—3

Fig. 1

Fig. 2

Fig. 3

Fig.4

Fig.5

Fig.6

FIG. 1 is a top plan view of a holder for tape cassettes showing my new design;

FIG. 2 is a bottom plan view thereof;

FIG. 3 is a side elevational view thereof;

FIG. 4 is a top plan view of a second embodiment of the invention;

FIG. 5 is a bottom plan view of the second embodiment; and

FIG. 6 is a side elevational view of the second embodiment.

I claim:

The ornamental design for a holder for tape cassettes or similar article, substantially as shown and described.
